UNITED STATES PATENT OFFICE.

LOUIS C. BERMAN, OF CHICAGO, ILLINOIS.

LIFTING JACK.

1,404,735.

Specification of Letters Patent. Patented Jan. 31, 1922.

Application filed October 1, 1920. Serial No. 414,096.

To all whom it may concern:

Be it known that I, LOUIS C. BERMAN, a citizen of the United States, residing at Chicago, in the county of Cook and State of Illinois, have invented certain new and useful Improvements in Lifting Jacks, of which the following is a specification.

My invention relates to lifting jacks and has for one of its objects the provision of a simple and efficient device of the character mentioned.

A further object is the provision of a simple and efficient jack capable of being easily and quickly set to raise weights at different heights.

A still further object is the provision of a simple and efficient manually operable means for preventing accidentally dropping a load when held on the jack.

Other objects will appear hereinafter.

An embodiment of my invention is shown in the accompanying drawings, forming a part of this specification, and in which—

Fig. 1 is a side elevation of a lifting jack embodying my invention;

Fig. 2 is an edge elevation of the same;

Fig. 3 is a vertical section;

Figs. 4 and 5 are fragmental vertical sections; and

Fig. 6 is an elevation taken as looking from line 6—6 in Fig. 4 of a handle and cam used in the device.

Referring more particularly to the drawings, I have indicated a bar 7, which in the present instance is a hollow tube, but may be made in any other desirable manner. At the lower end I provide a base 8 having an opening 9 for receiving the bar 7 when the latter is to be used in upright position, and an opening 10 for receiving the bar 7 when it is to be used in horizontal position, see particularly Fig. 3. I preferably make the base so that the bar 7 can be held in the base 8 with a single retaining pin 11, whether in upright or in horizontal position.

Slidably mounted on the bar I provide an upper member 12 and a lower member 13 each adapted to extend completely around the bar 7. The upper member 12 is provided with a boss 14 at one side with ribs 15 between the boss and its serrated lifting surface 16 so that the ribs communicate the pressure directly from the boss to the lifting surface 16. The boss 14 has a large perforation 17 in which a cylindrical lug 18 on a handle 19 is journaled. The lug 18 is

also hollow and a bolt 20 passed through the hollow of the lug to hold the handle in position. Also, on the handle is a perforated lug 21 extending toward the member 12. Pivoted on the lug 21 is a connecting link 22 which has its lower end pivoted in lower member 13. The lower end of link 22 may be pivoted in any desirable manner. I have indicated inwardly extending lugs 23 in member 13 which extend into grooves 24 in opposite sides of link 22, see Figs. 2 and 3.

In the lower member 13 is a recess formed to snugly receive a jaw 25 which has its teeth adapted to engage the bar 7. The opening 26 through the member 13 is preferably somewhat larger than the bar 7 in one direction so that the member 13 can rock to disengage the teeth of jaw 25 from bar 7, see Figs. 3 and 4. A spring 27 is placed between a suitable portion of member 13 and an arm 28 on link 22 so as to normally press the jaw 25 against the bar. Also, pressing downwardly on the lever in the operation of the device helps to hold the jaw 25 in engagement with the bar.

In the upper member 12 I provide a surface 29 disposed at an acute angle to the bar 7, and between the surface 29 and bar 7 I provide a jaw holder 30 in which is mounted a jaw 31. A spring 32 is disposed between a suitable portion of member 12 and the jaw holder 30 so as to normally press the surface 29 and hold the jaw 31 in engagement with the bar 7.

At one side of the member 12 is an opening 33 with grooves 34 in the inner walls of the sides of member 12. The grooves 34, one of which is shown in the drawings, extend inwardly from the opening 33 and provide bearings for the journals 35 of a handle 36. The handle may be made in any desirable manner, but I have indicated it as having two sides 37 and a wall 38. A cam 39 is provided between the walls 37 and spaced from the wall 38. Between the cam 39 and the wall 38 is disposed an angular arm 40 formed on or otherwise attached to the jaw holder 30.

At the top of the bar 7 I have indicated a jaw 41 secured to the bar by a bolt 42 and may be secured in any desirable manner. In the hollow top of the bar 7 I provide a member 43 which has a slot 44 therein engaging the bolt 42. This member 43 is useful to attach a wire to when it is desired

to stretch the latter. Then by placing member 12 against a post the wire can be stretched taut.

On one side of the member 41 I have indicated a wire clamp 45 having a handle 46 for operating same. Also, on member 12 I have indicated a wire clamp 45. These wire clamps may be used for stretching wires, and the like.

10 The jaw 41 may be used in connection with sliding member 12 to provide a vise and when so used it is sometimes convenient to place the bar 7 in opening 10 of the base 8 so that the jaws of members 12 and 41 will be vertical.

15 In the operation of my device the member 12 may be raised to the bottom of a load by simply pulling up on lever 19. In this upward movement the spring-pressed jaws 20 25 and 31 will slide up the bar 7. When the load is reached by member 12 the lever 19 is swung down and up to cause the members 12 and 13 to move up bar 7 step by step. In this step by step movement of the 25 members 12 and 13 the swinging of lever 19 will be limited in one direction by the end of link 22 engaging a shoulder 46 adjacent boss 14 and limited in its other direction by a projection 47 on link 22 engaging 30 boss 14.

35 A particular feature of this device is placing the parts in condition so that when there is a load on the surface 16, such load cannot be accidentally dropped. When it is 40 desired to lower a load on member 12, the parts are first placed in their positions shown in Fig. 1 and the handle 36 next placed in its position shown in Fig. 5 and lever 19 raised to its upper terminal movement which lowers member 12. Then lever 45 36 is moved to its position shown in Fig. 3 and the operator presses downwardly on a thumbpiece 49 on the side of member 13 as he lowers lever 19 to move member 13 down bar 7. This order of movements is continued until the load has been lowered the desired distance.

50 Sometimes it is desirable to move members 12 and 13 downwardly of bar 7 quickly, and in such cases handle 36 is moved to its position indicated in Fig. 4 so that wall 38 extends below member 12 in the path of extension 48 on member 13 when lever 19 is brought to its highest point. This moves 55 cam 39 against arm 40 and draws jaw 31 away from bar 7 and wall 38 tilts member 13 moving jaw 25 away from bar 7 so that both members 12 and 13, together with the parts mounted thereon, are freely slidable 60 up and down the bar 7, as desired.

I claim:

65 1. A jack comprising a bar; upper and lower members mounted on the bar; a jaw holder movably mounted in the upper member; a jaw in said holder; a jaw in the

lower member; a cam mounted in the upper member and having oscillatory and slideable movements; and an arm on the jaw holder engaging said cam and holding the latter in operative position.

70 2. A jack comprising a bar; upper and lower members slidably mounted on the bar, the upper member having slots therein; a jaw holder movably mounted in the upper member; a jaw in said holder; a jaw in the lower member; a cam having journals in said slots; and an arm on the jaw holder engaging the cam and holding the latter in operative position.

75 3. A jack comprising a bar; upper and lower members slidably mounted on the bar, the upper member having slots therein; a jaw holder movably mounted in the upper member; a jaw in said holder; a jaw in the lower member; a cam having journals in 80 said slots; a jaw attached to and spaced from the cam; an L-shaped arm attached to the jaw holder and extending between said jaw and cam holding the latter in position for moving the jaw holder; and a handle 85 attached to said jaw and cam.

90 4. A jack comprising a bar; upper and lower members slidably mounted on the bar, the upper member having an opening in one side and slots extending inwardly from said 95 opening; a jaw in each of the members; a spring pressing on the lower member normally holding the jaw therein against the bar; a spring-pressed jaw holder movably mounted in the upper member; a manually 100 operable cam having journals disposed in said slots and a portion adapted to engage the lower slidable member and move the jaw in the latter away from the bar; and an arm on the jaw holder engaging the cam for 105 holding the latter in operative position.

5. A jack comprising a bar; a hollow member slidably mounted on the bar and having an opening in one side; a jaw holder movably mounted in the hollow member; a handle in and having a pivotal connection with the hollow member with a portion extending out through said opening; a cam attached to the handle and spaced from a portion of the latter; a jaw holder in the 115 hollow member with an arm extending between the cam and said handle holding the handle and cam in operative positions; and a jaw in the jaw holder.

120 6. A jack comprising a bar; a hollow member slidably mounted on the bar with an opening in one side and slots in its inner walls extending inwardly from said opening; a jaw holder movably mounted in the hollow member; a handle in the hollow member having journals pivoted in said slots; a cam disposed between portions and spaced from another portion of said handle; an angular arm on the jaw holder extending between said portions of the handle and said cam 125 130

holding the handle in said hollow member; and a jaw in the jaw holder.

7. A jack comprising a bar; upper and lower slidable members on the bar; a boss and a shoulder on the upper member; a lever pivoted to said boss; and a link pivoted to the lower member and the lever, said link being adapted to engage the boss to limit the swinging of the lever in one direction and adapted to engage the shoulder to limit the swinging of the lever in the other direction.

8. A jack comprising a bar; upper and

lower members slidably mounted on the bar; a boss and a shoulder on the upper member; a lever pivoted to the boss; a link pivoted to the lower member and the lever, said link being adapted to engage the shoulder to limit the swinging of the lever in one direction; and a projection on the link adapted to engage said boss for limiting the swinging of the lever in the other direction.

In testimony whereof I have signed my name to this specification on this 28th day of September, A. D. 1920.

LOUIS C. BERMAN.
